United States Patent [19]

Sessions et al.

[11] Patent Number: Des. 366,408

[45] Date of Patent: **Jan. 23, 1996

[54] FOLDING KNIFE

5,060,379 10/1991 Neely 30/157

[75] Inventors: **George C. Sessions**, Milwaukee; **Bradford J. Parrish**, Oregon City, both of Oreg.

Primary Examiner—Philip S. Hyder
Attorney, Agent, or Firm—Foley & Lardner

[73] Assignee: **Fiskars Inc.**, Madison, Wis.

[57] CLAIM

[**] Term: 14 Years

The ornamental design for a folding knife, as shown and described.

[21] Appl. No.: 27,298

DESCRIPTION

[22] Filed: Aug. 18, 1994

FIG. 1 is a perspective view of a folding knife showing our new design;

[52] U.S. Cl. D8/99

FIG. 2 is a front elevational view thereof;

[58] Field of Search D8/98, 99; D22/118; 30/158, 159, 160, 161

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a front elevational view of a second embodiment of our new design, the left side and right side views and the top view thereof being similar to FIGS. 3, 4, and 5, respectively, but on a reduced scale;

FIG. 9 is a rear elevational view thereof; and,

FIG. 10 is a bottom plan view thereof.
